DEVICE FOR SHARPENING PHONOGRAPH NEEDLES

Merrill W. Ambrose, Boston, Mass., assignor of
one-half to Samuel Coty, Boston, Mass.

Application October 4, 1939, Serial No. 297,803

7 Claims. (Cl. 51—151)

This invention relates to apparatus for sharpening phonograph needles, particularly thorn or fibre needles, the points of which tend to become dulled more quickly than those of steel needles.

The principal purpose of the invention is to provide a simple and economical yet handy and efficient apparatus which may conveniently be employed by the user to sharpen the points of fibrous needles by reciprocating the handle of a holder arranged to maintain the needle point in proper contact with an abrasive substance. Another object is to provide a needle holder which may be quickly and conveniently adjusted so that the needle will assume any desired predetermined angle with respect to the abrasive surface; and which comprises separable elements which may be easily assembled for use or disassembled for packing or storage.

Further structural advantages of the improved device will be apparent from the following description of a recommended embodiment of the invention, taken in connection with the accompanying drawing, and will be pointed out in the appended claims. In the drawing,

Fig. 1 is a plan view of a base member forming part of the improved apparatus;

Fig. 2 is an end elevation thereof looking to the left of Fig. 1;

Fig. 3 is a side elevation, partly in section, of the assembled needle holder and handle;

Fig. 4 is a side view of the apparatus in position for use, with the base member shown in section; and

Figs. 5 and 6 are transverse sections taken on lines 5—5 and 6—6 respectively of Fig. 3.

In the particular embodiment chosen for the purpose of illustration, the needle sharpening apparatus comprises a base member 11 including upper and lower sections 12 and 13 respectively formed of wood or other solid material, the lower section having a covering 14 of soft fabric and said section being affixed to the upper section 12 by means of nails 15 or other fastenings which hold the covering in place. This covering serves as a cushion for the base member and also as a pad for wiping or polishing the surface of a phonograph record.

The top of the composite base 11 is provided with a strip of sand paper 16 or other abrasive substance, removably supported in metal clips 17 or otherwise attached upon the upper surface of the base member. A strip of rubber 18 or other friction material is inserted in the upper surface of the base member and extends parallel to the abrasive strip at a substantial distance therefrom, for a purpose which will hereafter become apparent; and the top of the base is formed with a groove or slot 19, located between the abrasive strip and the friction piece and extending parallel thereto across the base member. The slot

19 serves as a guide for a reciprocating handle 20 forming part of the needle holder assembly.

The needle holder comprises a tubular shaft 21 insertable in an opening extending at an oblique angle to the axis of the handle 20, and having slotted and threaded end portions; a nose piece or collet 22 adapted to contract one slotted and tapered end 23 of the tube 21, when threaded thereon to constitute a chuck for holding a needle 24 (Figs. 3 and 6); a coiled spring 25 surrounding the central portion of the shaft 21 and engaging the handle 20 at one end; a knurled disc or wheel 26 apertured to receive the shaft and having a key 27 engaging in a slot 28 of the shaft, so that the disc may slide longitudinally thereof but is prevented from rotating relative to the shaft; and a wing nut 29 threading on the outer end of the shaft and bearing against the disc 26 to hold the parts in assembled relation as shown in Fig. 3, with the handle disposed between the collet 22 and the spring 25.

It will be evident that the various elements of the needle holder may be separated from each other by removing the collet and the wing nut, and that the parts may be quickly assembled in operative relationship. It will also be apparent that the position of the disc 26 may be adjusted longitudinally with respect to the shaft by turning the wing nut, thereby to vary the distance between the disc and the point of the needle 24. The needle may be applied to the holder by inserting its butt end into the collet, or by dropping it point first through the opposite end of the tubular shaft; and is retained in place by tightening the collet.

The needle point is sharpened by placing the assembled needle holder (with the needle in place) on the base block 11 in the manner indicated in Fig. 4, and reciprocating the handle 20 in the slot 19 so that the shaft and needle are rotated by the frictional engagement between the knurled disc and the rubber strip 18. As the lower end of the handle, which may be notched at 30 to reduce its thickness, fits loosely in the guide slot 19, the needle holder is supported at the points of engagement between the needle and the abrasive and between the disc and the friction surface of the block, respectively, during operative movement of the handle. Hence, the angle of contact between the needle and the abrasive may readily be varied by adjusting the wing nut to change the position of the disc which rotates the shaft and needle, without disconnecting the parts and substituting a disc of larger or smaller diameter.

The conical point of the phonograph needle will thus have a uniform bearing on the abrasive strip, after the operative angle of the shaft has been properly adjusted for the particular needle. This feature is particularly important in sharp-

ening thorn or fibrous needles having ends which are not of the same contour. It will be understood, however, that the improved device may be used for sharpening steel or other phonograph 5 needles; and it will also be understood that the structural details of the apparatus herein illustrated and described may be varied without departing from the essence of this invention as defined in the following claims.

10 I claim:

1. Apparatus for sharpening phonograph needles comprising a base member, a strip of abrasive material on said base, a guide on said base extending parallel to the abrasive strip, a needle holder, a handle having an opening receiving the needle holder and having a lower end engageable with said guide during reciprocating movement of the handle, the holder being rotatable in the handle opening, a disc slidably connected to the holder and frictionally engaging said base for rotating the same when the handle is reciprocated, means for restraining rotation of the disc with respect to the holder, and means for holding the disc in adjusted position relative 20 to the holder, so that the holder will be supported at the desired inclination while the needle is sharpened.

2. Apparatus for sharpening phonograph needles comprising a base member, a strip of abrasive material on said base, a guide on said base extending parallel to the abrasive strip, a needle holder, a handle having an opening receiving the needle holder and having a lower end engageable with said guide during reciprocating 30 movement of the handle, the holder being rotatable in the handle opening, and a disc operatively connected to the holder for rotating the same when the handle is reciprocated, said holder comprising a shaft to which the disc is keyed for sliding movement longitudinally thereof, a spring surrounding the shaft between the handle and the disc, and a nut threading upon the outer end of the shaft and bearing against the disc for adjusting the longitudinal position of 35 the disc with respect to the shaft, whereby the angular operative relation between the needle holder and the abrasive strip may be varied according to the taper of the needle point.

3. Apparatus for sharpening phonograph needles comprising a base member, a strip of abrasive material on said base, a guide on said base extending parallel to the abrasive strip, a needle holder, a handle having an opening receiving the needle holder and having a lower end engageable 50 with said guide during reciprocating movement of the handle, the holder being rotatable in the handle opening, and a disc operatively connected to the holder for rotating the same when the handle is reciprocated with the needle point engaging the abrasive strip and the periphery of the disc engaging the surface of the base member, said opening in the handle extending at an oblique angle to the axis thereof, so that the handle assumes a substantially upright position 55 while the holder is supported at an inclination to the base, said disc being slidable longitudinally of the holder to vary the inclination thereof, and said guide consisting of a slot in the surface of the base member which receives the lower end 60 of the handle when the device is in operative position.

4. Apparatus for sharpening phonograph needles comprising a base member, a strip of abrasive material on said base, a guide on said base

extending parallel to the abrasive strip, a needle holder, a handle having an opening receiving the needle holder and having a lower end engageable with said guide during reciprocating movement of the handle, the holder being rotatable in the handle opening, and a disc operatively connected to the holder for rotating the same when the handle is reciprocated with the needle point engaging the abrasive strip and the periphery of the disc engaging the surface of the base member, said holder comprising a shaft to which the disc is keyed for sliding movement longitudinally thereof, a spring surrounding the shaft between the handle and the disc, and a nut threading upon the outer end of the shaft and bearing 10 against the disc for adjusting the longitudinal position of the disc with respect to the shaft, whereby the angular operative relation between the needle holder and the abrasive strip may be varied according to the taper of the needle point, 20 the handle, spring, disc, and adjusting nut being removable from the shaft, and the shaft having a removable collet for retaining the needle in the opposite end of the shaft, the handle being disposed between the collet and the spring. 25

5. A needle holding device adapted to be applied to a surface provided with an abrasive element for sharpening the needle point, said device comprising a tubular shaft having threaded ends, one end being slotted and tapered to receive a needle inserted therein or dropped through the opposite end of the holder shaft, a collet threading on the tapered end to retain the needle in place, a handle having an opening extending at an oblique angle to its axis for 30 rotatably receiving the shaft, the handle engaging the inner end of said collet, a coiled spring surrounding the central portion of the shaft and bearing against the opposite end of the handle, a disc slidable on said shaft and keyed thereto, and 40 a nut threading on said opposite end of the shaft and bearing against the disc, whereby the longitudinal position of the disc with respect to the shaft may be adjusted by turning the nut, all of said parts being separable from each other. 45

6. Apparatus for sharpening phonograph needles, comprising a base having an abrasive strip, a handle, a needle holder carried by the handle and rotatable relative thereto, a disc connected to the holder and movable longitudinally thereof, the periphery of the disc frictionally engaging said base to rotate the holder, means for holding the disc in adjusted position relative to the holder so that the holder is rotated and supported at the desired inclination when the handle 50 is reciprocated to sharpen the needle, and means for guiding the device in a path parallel to the abrasive strip during reciprocation of the handle. 55

7. Apparatus for sharpening phonograph needles, comprising a base having an abrasive strip 60 thereon and a slot parallel to said strip, a handle having an end portion received in said slot so that the handle is guided thereby when it is reciprocated, the handle having an opening extending therethrough at an oblique angle to the 65 axis thereof, a needle holder rotatably supported in said opening, and a disc connected to the holder and engageable on the base for rotating the holder when the handle is reciprocated in said slot, the handle remaining in substantially 70 upright position during operative movement thereof, while the holder is supported at an inclination to the base.

MERRILL W. AMBROSE.
